7481X

H. Moses.
Can for Carding Mach.
Patented Mar 12, 1833.

March 12 1839

114217 DeLorean M. D. & Patterson Claw Society

Section Patent

This Schedule is referred to in this Section Patent and is a working part of the same containing a description in the words of the said M. D. DeLorean of his Improvement in the Construction of Cast Iron for the manufacture of Cotton-Flax and Wool.

To all to whom these presents shall come. We the inventors that is to say M. D. DeLorean in the County of Lucy State of Connecticut have invented a new and useful Improvement in the Construction of Cast Iron for the manufacture of Cotton-Flax and Wool and that the following is a full and exact Description of the construction and operation of the said Improvement as invented and improved by us.

The drawing accompanying this Specification A is the bar or copper wire B is a loop made of the same iron or cast iron as may be best adapted and for vehicle improvement the joint is shown.

Witnessed

DeLorean M. D.

1142

Abner W. Whiting
Clark Green

(Do on post office)

168 W. 97